GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

SEWING-MACHINE GUIDE.

Application filed February 14, 1921. Serial No. 444,775.

To all whom it may concern:

Be it known that I, GEORGE S. GATCHELL, a citizen of the United States, residing at Roselle Park, in the county of Union and State of New Jersey, have invented certain new and useful Improvements in Sewing-Machine Guides, of which the following is a specification, reference being had therein to the accompanying drawings.

10 This invention relates to a guide for sewing machines and has for its primary object to provide a simple and effective device for opening out the uniting seams of superposed plies of fabric which have been 15 stitched together and presenting them in this condition to a stitching mechanism for the application of a covering or fastening seam or seams at their junctions.

In its preferred construction the elements 20 of the device are applied to the end cap of the work-arm of the sewing machine in advance of the presser-foot but near enough thereto to cooperate with the presser-foot and a rib or keel formed on the under side 25 thereof to properly guide the work to the stitching mechanism. These elements include a work-supporting block adjustably secured to the cap and having a seam opening and guiding ridge or edge raised from 30 its work-supporting surface and which is adapted to enter the crease between the plies of the previously formed seam and spread the edges of the two pieces of fabric. Co- 35 operating with and overlying the work-supporting surface of the guide-block are two yielding and adjustably mounted sheet-metal guiding wings having their shanks secured to the opposite sides of the end cap. The ends of these guiding wings are main- 40 tained in a substantially horizontal position and enter between the body fabrics and their opened out marginal portions and have their guiding edges spaced apart to afford a channel for the passage of the ma- 45 terial.

The class of stitching mechanism prefer- 50 ably employed comprises two reciprocating needles spaced apart sufficiently to penetrate the marginal portions of the fabric on opposite sides of the uniting seam, combined with looper mechanism for interlooping with the needle-threads a looper or covering thread overlying the said marginal portions of the fabric. This device is, how- 55 ever, not confined to use with this specific

type of stitching mechanism as obviously any suitable form may be employed.

In the drawings, Fig. 1 is a side elevation of the end of the work-arm showing my invention applied thereto in its relative position with respect to the presser-foot and needle. Fig. 2 is a sectional elevation of the upper part of the work-arm showing the work in position in the guide, the section being taken substantially on the line 2—2, Fig. 1, looking in the direction of the arrow. Fig. 3 is a section similar to Fig. 2 substantially on the line 3—3, Fig. 1, also looking in the direction of the arrow. Fig. 4 is a perspective of the end of the work-arm showing the needles and presser-foot and the position occupied by the work as it is passing through the device. Fig. 5 is an end elevation of the cap. Fig. 6 is a plan view of the cap removed from the work-arm. Fig. 7 is a perspective of the guiding block removed.

The elements in my device are disclosed as applied to the cap on the end of the tubular work-arm of the sewing machine, said arm being indicated by the reference numeral 1. The cap 2 closes the open end of the arm and is secured thereto by a hinged extension 3 slidably fitting in a slot 4 in the side of the work-arm, this slot being provided with inclined side walls. The hinged extension 3 is secured so as to prevent removal entirely from the arm by a screw 5, but this screw passes through a slot in the arm (not shown) allowing the cap to be drawn outwardly sufficient to turn out of the way about the hinge 6 as a pivot. The looper mechanism is enclosed within this cap substantially as disclosed in the patent to Molyneux No. 1,084,223, dated January 13, 1914, and cooperates with the needles 7 to form the stitches.

Secured on the end of the cap 2 by means of a screw 8 is a work-supporting and guiding block 9 provided with an enlarged opening 8' through which the screw 8 passes in order that the block may be adjustably secured to the end of the cap. This block, as shown, is provided with a substantially central upwardly directed ridge or edge 10, the forward end of which is rather abrupt in height but which is gradually reduced in the direction of feed so that the rear end 11 practically merges into the sides of the guide. The upper surface of this guide on

opposite sides of the ridge 10 is curved outwardly to the edges 12 of the guide as shown in Fig. 5. This guide may be secured directly on the front face of the cap 2 but is 5 preferably set into a recess 13.

Cooperating with and overlying the work-supporting surface of the guide-block 9 are two yielding and adjustably mounted sheet-metal guiding wings 14 and 15 having their shanks 16 and 17 secured to opposite sides of said cap by suitable screws 18. The shanks of these wings are bent outwardly from the cap at 19 and 20 so that a portion of the shanks between the screws 18 and 10 the guiding portions 14 and 15 is spaced from the walls of the cap. Passing through this portion are screws 21 and by adjusting these screws inwardly or outwardly the guiding wings 14 and 15 may be adjusted 15 toward or from each other and the supporting surfaces of the guide 9, thus varying the space between their guiding edges and also the distance between these edges and the surfaces of the guide 9. These adjustments 20 may be made because the shank portions 19 and 20 are flexible, these wings being preferably made of resilient sheet-metal. It will be noted in the drawings that these wings 25 are provided with curved guiding edges 22 and 23 which are located on opposite sides of the upwardly extending ridge 10 and form a channel flaring to the front for the passage of the work, the ridge 10 extending 30 into this channel as shown.

35 The presser-foot 24 preferably employed in connection with this device is provided on its under side with a longitudinally extending keel or rib 25 which also extends in the direction of the feed of the work and is located in substantially the same vertical plane as the ridge 10. The guiding elements 40 9, 14 and 15 are located preferably just in advance of the forward end of the presser-foot as indicated in Fig. 1.

45 The upper side of the end cap is flattened to fit the under side of the throat-plate 26 provided with slots through which projects a feed-dog 27 cooperating with the presser-foot to feed the work past the stitching mechanism.

50 The stitching mechanism employed preferably comprises two reciprocating needles spaced apart sufficiently to penetrate the marginal portions on opposite sides of the uniting seam, combined with a looper mechanism for interlooping with the needle-threads a looper or covering thread overlying the said marginal portions of the fabric, that is, two needles and one thread-carrying looper forming a three thread chain-stitch. 55 Stitching mechanism of this type is disclosed for instance in the above mentioned patent to Molyneux and is not illustrated herein. It is not necessary, however, that this specific type of mechanism be employed as it is

obvious that any suitable mechanism may be used.

In operation two pieces of fabric 28 and 29 which have been sewed together by a line of stitches S adjacent the marginal edges 70 thereof are inserted between the wings 14 and 15 and guide-block 9 with the ridge or edge 10 extending between the marginal edges and tracking with the under side of the uniting seam as shown in Figs. 2 and 4. 75 The two marginal portions 30 and 31 are bent outwardly by the guiding block 9 between the wings 14 and 15 and this block together with the edges of the wings contacts with the uniting seam. The portions of the 80 fabric above the seam are pressed downwardly by the action of the presser-foot and are pressed against the top of the outwardly bent marginal portions as shown in Fig. 3 immediately before the fabric reaches the 85 stitching point so that they may be secured in this position by the two lines of stitches S' formed by the multiple needles 7. The rib or keel 25 on the under side of the presser-foot tracks the upper side of the uniting 90 seam as shown in Fig. 3 and thus assists the ridge of the lower guide 9 in properly guiding the fabric past the stitching point. Thus the ridge 10 and the keel 25 track the seam both on the top and under side thereof. 95 After the work is started it is unnecessary to further guide the seam by hand and the operator may be preparing a new piece of work for insertion in the guides while the piece which is already inserted therein is 100 passing the stitching mechanism.

While the embodiment shown is the preferred construction it will be obvious that the present improvement is susceptible of considerable modification without departing 105 from the scope of the invention.

Having thus set forth the nature of the invention, what I claim herein is—

1. A sewing machine guide formed with a work-guiding channel having side walls with 110 curved guiding edges separated to form a longitudinally extending opening flared at its entrance, a guide rigidly supported for vertical adjustment within said channel and provided with an upwardly extending guiding ridge or edge in registry with said longitudinal opening, and means whereby the channel side walls may be laterally adjusted toward or from the guide.

2. A seam guide for tubular arm sewing 120 machines comprising a cap adapted to be secured to the end of said arm, a guide rigidly secured to said cap and adapted to open out and spread the edges of two pieces of fabric adjacent a seam therethrough, said guide comprising an upwardly directed guiding ridge or edge extending in the direction of feed, and a pair of yielding guides 125 adjustably mounted on the cap on opposite sides of said first guide and terminating in 130

edge portions adjacent to but spaced from the upwardly directed guiding ridge or edge.

3. A seam guide for tubular arm sewing machines, comprising a cap adapted to be secured to the end of said arm, a guide adjustably secured to said cap and adapted to open out and spread the edges of two pieces of fabric adjacent a seam therethrough, said 10 guide comprising a substantially vertically directed guiding ridge or edge extending in the direction of feed, a pair of wing guides secured to the cap and terminating in edge portions adjacent to but spaced from and on 15 opposite sides of said guiding ridge or edge, and means whereby said wing guides may be adjusted toward and from the first said guide and each other.
4. In a sewing machine having a multiple 20 needle stitch-forming mechanism, a presser-foot provided with a keel or rib on its under side extending in the direction of feed, a guide adapted to open out and spread the edges of two pieces of fabric adjacent a seam 25 therethrough, said guide being in advance of the stitching point and comprising a rigidly mounted element having an upwardly directed guiding ridge or edge extending in the direction of feed, and yielding 30 mounted guiding elements terminating in edge portions adjacent but spaced from and on opposite sides of said upwardly directed ridge or edge.
5. In a sewing machine having a multiple 35 needle stitch-forming mechanism, a presser-foot having a longitudinal keel or rib on its under side, a guide adapted to open out and spread the edges of two pieces of fabric adjacent a uniting seam therethrough, said 40 guide being spaced from and in advance of the presser-foot and including a rigidly mounted member having an upwardly directed separating edge adapted to enter between the margins of the united fabric 45 and adapted to be tracked by the uniting

seam, a work-support, and yielding wings overhanging said work-support and terminating in edge portions adjacent to but spaced from and on opposite sides of said upwardly directed separating edge, said 50 edge and keel or rib on the presser-foot being located in substantially the same vertical plane.

6. A sewing machine guide comprising a central guide element having an upwardly 55 directed ridge, a pair of laterally yielding guide arms disposed at opposite sides of said ridge, and means for laterally adjusting said guide-arms.

7. A work-guiding attachment for cylinder bed sewing machines comprising an end-cap, a central guiding element secured to said end-cap and formed with an upwardly extending guiding ridge, a pair of yielding arms each secured at one end to said end-cap and at its other end terminating in a guiding edge adjacent said ridge, and means including adjustment screws engaging said arms between their ends for adjusting the free ends of said arms laterally of said guiding ridge. 60

8. In a sewing machine guide, in combination, a vertically adjustable central guiding element formed with an upwardly directed ridge, and a pair of laterally adjustable 75 guiding wings disposed one at each side, respectively, of the central guiding element.

9. The combination with the end-cap of a cylinder bed sewing machine, of a central guide secured to the end-cap and having an 80 upwardly directed guiding ridge, and a pair of guide-wings secured to the side walls of the end-cap below the level of the central guide and extending upwardly and forwardly in spaced relation with said end-cap 85 and terminating at their free ends closely adjacent said ridge.

In testimony whereof, I have signed my name to this specification.

GEORGE S. GATCHELL.
